UNITED STATES PATENT OFFICE.

WILLIAM GORDON, OF UNION, NEW JERSEY.

PIPE WRENCH.

Application filed March 22, 1922. Serial No. 545,796.

This invention relates to improvements in pipe wrenches.

The principal objects of this invention are to produce a quick-acting pipe wrench construction which may be instantaneously manipulated into proper adjustment for the purpose of procuring an effective grip on a pipe or the like without the usual tightening-up by a screw and which grip may be instantaneously released and retaken; to produce a construction which will enable a fineness of adjustment of the jaws in relation to the pipe to be had so as to cause a more secure grip of the pipe or the like in manipulation thereof; to produce a pipe wrench in which one of the gripping jaws is arranged to swing on a fixed shank at a point intermediate the ends thereof and the swinging movement thereof is greatly facilitated; to produce a pipe wrench in which one of the gripping jaws is mounted to slide along a shank into gripping engagement with a swinging jaw; to produce a pipe wrench in which the sliding jaw is slideable along a portion of the shank above the point at which the swinging jaw is connected to the shank; to produce a pipe wrench of the type above specified in which the sliding jaw may be automatically retracted from its engaging position and a double release is provided; to produce a pipe wrench which may not only be more quickly, readily and accurately adjusted to fit a pipe but may be released more readily and easily than has heretofore been possible for the purpose of taking a new hold on said pipe by a movement of the swinging jaw only, viz, by a pressing of the thumb of the user on the rear or operating part thereof, and which furthermore will, unless so manipulated at the operating part, securely grip and produce a locking engagement between the jaws on the pipe; to produce an instantaneously-releasable pipe wrench in which the manipulation of the swinging jaw may be employed in combination with the manipulation of the sliding jaw to procure an effective grip; to produce a pipe wrench in which the release members are conveniently located, viz, the release member for the automatically retractable jaw is located at one side of the wrench for operation by the forefinger and the release or opening member for the swinging jaw is located opposite the same for operation by the thumb, so that the wrench may be operated by one hand.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a side elevation having parts broken away and shown in section of a pipe wrench embodying my invention;

Fig. 2 is a side elevation of a wrench gripping a piece of pipe;

Fig. 3 is a section on the line 3—3 of Fig. 1 looking in the direction of the arrow;

Fig. 4 is a section on the line 4—4 of Fig. 1;

Fig. 5 is a diagrammatic view showing the relationship of the various engaging members with the rack of the sliding jaw;

Fig. 6 is a side elevation of a modified form of my invention;

Fig. 7 is a plan view of the wrench shown in Fig. 6;

Fig. 8 is a section on the line 8—8 of Fig. 6;

Fig. 9 is a view in side elevation of the pivotally movable jaw separated from the other parts of the wrench; and

Fig. 10 is a perspective view of the operating hood for the pivotally movable jaw shown in Figs. 6 and 7.

Referring now to these drawings, which illustrate a preferred embodiment of my invention, 1 indicates the shank of a wrench which is relatively stationary and, as illustrated, is composed of a relatively thick body portion having a notch or pawl housing 1^a formed therein and a top portion 1^b of reduced size. On the body portion of the shank is mounted a rearward extension 3 of a swinging jaw 4 which, as shown, is pivoted at 2. This swinging jaw, as shown, is provided with a guiding socket 4^a and the top of the reduced portion of the shank is provided with a pin 1^c which fits into said guiding socket and is adapted to guide the jaw in its pivotal movement in relation to the shank and to take up lateral strain thereon, and said jaw furthermore has a tail piece 3^a integral with the extension 3 and extending to the opposite side of said pivot. This tail piece 3^a is normally held in elevated position by means of a flat spring 3^b.

so that the jaw 4 will be resiliently pressed into its most forward position. The sliding jaw 5 is provided with a socket 5^a and is mounted to slide on the reduced shank portion 1^b between the jaw 4 and the body portion 1 of the shank at which point the said pivotally movable jaw 4 is pivoted to the shank. Said sliding jaw 5 is provided with a rearwardly extending rack portion 6 having a series of teeth 7 disposed inwardly toward the shank. Housed within the housing 1^a in the shank are a series of three rack engaging members 8, each of which is provided with rounded rear ends 8^b and is pivotally mounted in a rounded socket 1^a at the lower end of said housing 1^a. Said rack engaging members 8 are provided with outwardly extending teeth 8^c and are each normally pressed independently into engagement with the teeth 7 of the rack 6 by means of a flat spring 9 having divided legs pressing against each of such rack engaging members 8 independently.

The sliding jaw 5 is, as shown, normally drawn to its rear position by a spring 10 stretched between a pin 11 at one end of the shank and an eye 12 on the rack 6. The spring, rack and rack engaging members are preferably all assembled in the rear end of the wrench and a casing 13 is slid over the same and suitably connected in position by pins 13^a—13^b to the shank, so as to enclose all the parts and retain the same in their relative operative positions. The engaging members 8 for the rack of the sliding jaw are disposed one alongside of the other and in such relationship to the rack as to subdivide or split up the space between a tooth thereof, as will be seen by an examination of Fig. 5, in which 6 is the rack, 8, 8' and 8'' indicate the rack-engaging members, and thus to permit a fine adjustment to be made and a tighter grip to be obtained upon the pipe or the like which it is desired to manipulate.

Each of the rack engaging members is provided at its forward end with shoulders 8^d and these shoulders are preferably engaged conjointly by a lifter bar 14 which is connected to a finger actuated bail portion 15 extending to the front side of the wrench at a position substantially opposite to the releasing tail piece, so that in the operation of the wrench the release of the sliding jaw may be effected by one of the fingers, while the tail piece may, if desired, be operated to release by the thumb of the hand, thus resulting in a double release and double positioning means and in a convenient positioning and easily operable relationship of the operating parts of the wrench so that the wrench may be manipulated by one hand.

In the embodiment shown in Figs. 6 to 10, which is my preferred embodiment of my wrench, a swinging jaw 20 is provided with

a tail piece 23 and fulcrumed on a shank 21 of the wrench by means of a fulcrum projection 22 which is disposed between the ends of the tail piece 23 of said jaw and seats in a notch 24 in said shank 21. The jaw is held in place on the shank and manipulated to swing about its fulcrum projection by a separate hood 25 which is pivoted at 26 on the shank inwardly of said fulcrum projection and in substantial alignment with the point about which the jaw swings on said projection. A very short stiff leverage action between the end of the hood 25^a and said fulcrum and pivot will be produced when pressure is applied at the gripping end of said jaw and transmitted to the end 25^b of the hood but a long lever easy of manipulation will be provided when pressure is applied at the oposite end 25^b of said hood and the swinging jaw may therefore be more readily, easily and quickly manipulated than has heretofore been possible. The tail piece 23 of the said jaw is provided with a spring 27 to normally maintain the said tail piece in elevated position and to swing the same about the fulcrum so as to swing the jaw into gripping position.

In other respects the construction shown in said Figs. 6 to 10 is the same as that above described in relation to Figs. 1 to 5.

The operation of the wrench shown in Figs. 1 to 5 is as follows:

Assuming that the wrench is in the position shown in Fig. 1 and it is desired to grip a pipe or the like, the swinging jaw 4 is swung open by pressure on the tail piece 3^a and the sliding jaw 5 is moved upwardly usually by the thumb into gripping engagement with the pipe or the like and the wrench will then assume the position shown in Fig. 2. Wrenches of this character very often "freeze" or lock on the pipe in this position and it then becomes impossible to release the same. In this embodiment of the invention, however, when it is desired to release the wrench from the pipe to which it is so locked, the releasing pawl 15 is pressed inwardly and the sliding jaw 5 instantaneously and automatically by the action of the spring 10 is pulled away from gripping relationship with the object gripped thereby.

The operation of the wrench shown in Figs. 6 to 10 is in all respects similar to that hereinabove described, except that pressure is applied on the end 25^b of the hood 25 to release instead of directly on the end piece and except that when pressure is exerted at the gripping end of the jaw 20 a very short stiff leverage action or a locking joint will be produced between the end 25^a of the hood and said fulcrum and pivot.

The fineness of adjustment in the rack engaging members enables the accurate en-

gagement and therefore the more firm gripping of pipes of greater variation in diameter than could be gripped without such fine adjustment, and without the usual tightening up by screw-adjusting means, and in view of the ability to release instantly by the retracting spring 10, the swinging jaw may be opened at the same time that the sliding jaw is pushed up for the purpose of getting a tighter grip, and this may be done without fear of sticking or jamming of the parts.

It will be obvious that an extremely quick-acting mechanism is produced which may be applied to and released from a pipe or the like instantly. Either of the constructions hereinabove described may be operated easily and quickly by one hand of the operator.

Having described my invention, I claim:—

1. In a pipe wrench, in combination, a stationary shank having an upper slide-bar portion and a pivot-bearing below said portion, an upper jaw having a rearward extension disposed at the rear and substantially parallel to said slide-bar portion and pivotally mounted on said shank below said slide-bar portion, said parts being arranged to cause said upper jaw to be movable transversely across and adjacent to the upper end of said slide-bar portion of the shank, another jaw slideable on the slide-bar portion of said shank and having a movement limited by the bottom of the upper jaw and said pivot-bearing, releasable means for adjustably retaining said jaws in varying positions relative to each other to grip a pipe, and said rearward extension having an operating part below said pivot for swinging said jaw relatively to the slide-bar portion of said shank.

2. In a pipe wrench, in combination, a stationary shank, a jaw having swinging movement only and provided with a rearwardly-extending portion fulcrumed between its ends on said shank, an operating member for said swinging jaw having a connection with said fulcrum portion and independently pivoted on said shank to facilitate the movement of said fulcrumed part, and another jaw movable longitudinally on said shank and relatively to said swinging jaw to grip an object therebetween.

3. In a pipe wrench, in combination, a stationary shank, a jaw having swinging movement only and provided with a rearwardly-extending portion fulcrumed between its ends on said shank, a hood independently pivoted on said shank in substantial alignment with said fulcrum and extending unequal distances to opposite sides of said fulcrum, whereby the shank swing-

ing jaw is held in place in its mounted position on the shank and an increased leverage is produced for manual actuation of the 65 swinging jaw.

4. In a pipe wrench, in combination, a stationary shank, a jaw having a loose connection with one end of said shank and also having a rearward extension mounted on 70 said shank to swing about an axis between its ends and having an operating part at the rear of said axis for swinging said jaw about the same, a sliding jaw movable on said shank between the said first mentioned 75 jaw and its mounting, means mounted in said shank for adjusting the sliding jaw in its sliding movement, operating means extending to one side of the shank for releasing said adjusting means and manually-movable leverage-increasing means at the opposite side of said shank for engaging said rearward extension at the rear of the axis about which it swings to actuate the swinging jaw in its swinging movement.

5. In a pipe wrench, in combination, a stationary shank comprising a member extending substantially the entire length of the wrench, a swinging jaw having an integral portion fulcrumed on said shank between the ends thereof, a longitudinally-movable jaw having a socket slideable on said shank, manually-releasable spring-operable means extending to one side of said shank for adjusting the sliding jaw in its 90 sliding movement, a hood at the opposite side of said shank pivoted on the shank in substantial alignment with said fulcrum, extending unequal distances to opposite sides of said fulcrum and having a tail piece for 95 manipulating said swinging jaw.

6. In a pipe wrench, in combination, a stationary shank comprising a member extending substantially the entire length of the wrench and provided at its outer end with a projection, a swinging jaw having an integral portion fulcrumed on said shank between the ends thereof and having a slot forming a sliding connection with the projection at the end of said shank, a longitudinally-movable jaw having a socket slideable on said shank, manually-releasable spring-operable means extending to one side of said shank for adjusting the sliding jaw in its 105 sliding movement, a hood pivoted at the 110 opposite side of said shank in substantial alignment with said fulcrum, extending unequal distances to opposite sides of said fulcrum, and having a tail piece for manipulating said swinging jaw.

In witness whereof, I have signed my name to the foregoing specification.

WILLIAM GORDON.
